BOTTOM HOLE CHOKE

John R. Yancey, Houston, Tex., assignor to J. C. Nicklos

Application March 27, 1934, Serial No. 717,569

11 Claims. (Cl. 166—2)

The invention relates to an improvement in chokes to control the flow of fluid, particularly of the type positioned in the pipes of a flowing well in order to restrict the flow therefrom.

5 It is one of the objects of the invention to provide a combination tubing and choke assembly wherein the choke assembly may be positioned in and removed from the well tubing while the tubing remains in position in the well.

10 Another object of the invention is to provide a removable well choke which can be run into or removed from position in the tubing by a setting tool.

Another object of the invention is to provide 15 a replaceable bottom hole choke assembly so that accurate gauging of the well can be had by replacing the choke without removing the tubing from the well.

Another object of the invention is to provide 20 a bottom hole choke which is readily replaceable and through which circulation may be had in order to wash the well.

Still another object of the invention is to provide 25 a bottom hole choke which may be operated to wash the well but which will move to closed position to accomplish the choking action automatically when flowing of the well is commenced.

A still further object of the invention is to provide 30 a replaceable bottom hole choke which may be latched in position in the well bottom.

It is also an object of the invention to position the choke in any of the flow lines or tubing at the surface of the well because the choke may be readily positioned and removed.

35 Other and further objects of the invention will be readily apparent when the following description is considered in connection with the accompanying drawing, wherein:

Fig. 1 is a central, vertical, sectional view showing the choke assembly latched in position in the tubing with the parts arranged as they will be during the flowing of the well.

Fig. 2 is a central, vertical, sectional view of the choke being removed from the well with the 45 tool used to remove the choke shown in position.

Fig. 3 is a side elevation of the choke with the setting tool connected thereto illustrating one manner in which the choke may be lowered into the well.

50 Fig. 4 is a section taken on the line 4—4 of Fig. 2 and looking in the direction of the arrows.

As is well understood in the flowing of wells to obtain oil and gas particularly, it is desirable to choke down the production of the well in 55 order to comply with various statutes and in

order to control the escape of oil and gas from the formations. It is the usual practice after the well has been drilled to lower a tube of relatively small diameter into the well in order to facilitate the removal of the fluid. Such a tubing is indicated at 2 in Fig. 1, and is formed by coupling sections of pipe together until the lower end of the pipe has reached the elevation of production. It is not uncommon for a strainer or filter to be carried by the lower end of this tube, 10 but in some instances the strainer is carried by the casing. The present invention is susceptible for use in either type of equipment and is shown as located in the tubing 2 intermediate 15 the ends thereof.

The lower end 3 of the tubing may serve as a support for the strainer, or other construction. The device has been illustrated as embodying a coupling 4 and a housing 5. These two parts serve as connecting members between the 20 tubing portions 2 and 3 and the tubing will be assembled with the coupling and the housing in position at the time it is lowered into the well. The housing 5 is in the nature of a nipple which is formed with a seat 7 adjacent the lower end 25 to provide a stop for the choke assembly which is indicated generally at 8. It is contemplated that the choke assembly 8 will fit snugly within the housing 5 so that there will not be any leakage around the choke assembly. In order, however, to avoid leakage, a plurality of sealing rings or cups 9 may be carried by the choke assembly 30 if desired.

Heretofore considerable difficulty has been encountered in choking the flow of fluid from a 35 well at the surface because of the enormous pressure encountered and difficulty has also been had with attempts to adjust the choke at the bottom of the well due to the expansion and contraction of the materials and to the inaccuracy of adjustment obtainable. With bottom hole chokes heretofore when the choke became worn and inaccurate it was then necessary to pull the entire string of tubing in order to replace the choke. With the present invention, however, it is contemplated that the choke or choke assembly 8 40 will be made up as a unitary device as best seen in Fig. 3, which could either be dropped into the tubing and settled by gravity by the set up, or it could be lowered into the tubing by the setting 45 tool 10.

Fig. 3 shows the setting tool 10 as being equipped with a plurality of expandable fingers 11 which are arranged to engage the inside surface 12 of the choke assembly, it being under- 55

stood that the choke assembly will be passed on to the fingers 11 while the device is at the surface. The tool 10 can then be run into the well either on a string of rods or cable, and the choke passed into the housing 5 so that it will assume its proper position, such as shown in Fig. 1.

In order that the choke assembly will be retained in its proper position in spite of the pressure in the well bore, the latching fingers 15 have been provided in the coupling 4. These latches are held in position by screws as at 16 and are curved so that they project into the normal passage in the tubing. These fingers are inclined downwardly to provide a shoulder 17 and the contact end 18. When the choke assembly is lowered into position it will engage the shoulder 17 on the fingers and cause them to be spread apart so that the assembly can pass into the housing 5. As soon, however, as the upper end 20 of the assembly passes the contact ends 18, the latches will spring inwardly to hold it against upward movement. An upward pull on the setting tool 10 results in the withdrawal of the tool from the assembly so that it is properly positioned for operation.

When it is desired to remove the choke assembly a spear or other suitable pulling tool such as 21 can be lowered into the well bore to engage it. This tool 21 is shown as having an enlarged portion 22 which engages the latches 15 to present them outwardly beyond the normal periphery of the choke assembly 8. Projecting below the enlarged portion 22 on the tool 21 is the spear or grapple 23 which is arranged to engage the inside surface 12 of the choke assembly so that the assembly can be removed. Any type of releasable spear can be used for this purpose.

The choke assembly per se is made up of the base 30 which has an enlarged chamber 31 therein. To the upper end of this base 30 is a connection 32 which may serve as a support for the sealing members 9 and which is surmounted by the cap 34 of the choke assembly. The choke member 35, by which restriction of the flow is obtained, is positioned in the chamber 31 and has a tapered upper end 36 thereon which is arranged to engage with a cooperating shoulder 37 on the lower end of the connection 33. Thus, these parts will be accurately fitted in order to form a seat for the choke member during the choking operation. The choke member 35 is shown in section in Fig. 4, and is made up of the body portion 39 and the wings 40 thereon, so that a flow of fluid may be had around the outside of the choke member through the passages 41 which are defined by the body and wings of the choke member and the chamber 31.

The wing 40 of the choke member extends below the body, as seen at 42 in Fig. 1, and there is a pressure chamber 43 formed in the lower end of the body which is reduced to form the orifice 44.

The choke member is freely movable in the chamber 31 and has a limited sliding movement in the chamber. Fig. 1 shows the choke member in upper position where the choking action is performed, whereas Fig. 2 shows the choke member in its lowermost position so that there may be a flow of fluid around the choke member in either direction. This may be said to be the inoperative or non-choking position because the flow will not be restricted to the choke area. The upper ends of the wings 40 are cut away to form an opening 45 which facilitates the flow of

fluid around the choke. In operation of the device the tubing may be positioned without the choke assembly. The assembly can then be lowered into the tubing either with the setting tool 10, or it may be dropped into the tubing 5 so that it may fall by gravity. In either instance it will pass the latches 15 and seat upon the shoulder 7. If it is then desired to wash the well or circulate fluid therethrough, the pressure downwardly on the choke member will cause it to move to the position shown in Fig. 2, so that a considerable volume of liquid may be pumped downwardly around the choke member. When, however, the well is ready to produce, the pressure relieved inside of the tubing 2 and the 15 pressure in the well will then force the fluid upwardly through the tubing. When this pressure is exerted below the choke member in the pressure chamber 43 it will cause it to move upwardly from the position shown in Fig. 2 to 20 the position shown in Fig. 1 where a full choking action is obtained, because the parts 36 and 37 will set to form a seal, except for the passage 44. The greater the pressure in the well, the greater will be the setting of the choke member in position.

If, for any reason, however, the pressure in the well falls below that required to hold the choke in position the choke will fall by gravity and the production of the well will be thus increased 30 by the flow of fluid around the member. When the pressure increases, however, the member will again rise upwardly and choke the flow in the manner intended. If the choke member becomes worn, or the amount of production from 35 the well is to be changed, it is only necessary to go into the well with the tool 21 which moves the latches 15 to an inoperative position and grasps the choke assembly by means of the spear 23 so that the choke assembly can be removed 40 from the well. The choke member 35 can be replaced with a member of the proper size, or with a choke member which is true to gauge. The choke assembly can then be lowered into the well as previously described, and a simple and 45 economical operation of the well obtained.

While the invention has been shown and described particularly as being positioned in the bottom of the well on the tubing the pipes 2 and 3 may be any flow line pipes. The choke assembly may be inserted and removed from such flow line pipes in exactly the same manner as described regardless of whether the choke is in a vertical or horizontal position.

The invention broadly contemplates a replaceable choke member which can be positioned and removed without molesting the tubing, and through which the well may be washed or produced as desired.

I claim:

1. A bottom hole choke for well tubing adapted to be lowered into and removed from the well as an independent member including a choke assembly, a choke member, cooperating means on the choke and the tubing to hold the choke in position, said choke member being freely movable in said assembly to choking or non-choking position, said means comprising a spring latch operable as the choke moves into position in the tubing.

2. A bottom hole choke for well tubing adapted to be lowered into and removed from the well as an independent member including a choke assembly, a choke member, cooperating means on the choke and the tubing to hold the choke in

60

70

75

position including spring fingers, said choke member being freely movable by gravity to non-choking position but adapted to be raised to choking position by the flow of fluid to be choked.

5 3. In combination with a well tubing, a well choke assembly adapted to be lowered into and removed from the tubing, and latching means consisting of spring fingers to automatically latch said choke assembly in position, said choke assembly comprising a housing formed with a restricted lower end and a second restriction spaced upwardly from its lower end, and a choke member formed with an upwardly tapering passage mounted within said housing for sliding movement between the restricted lower end thereof and said second restriction.

4. In a well, a tubing providing for flow of fluid from the well, a hollow choke assembly adapted to be lowered into said tubing to control flow of fluid therethrough from the well, and to be removed from said tubing without removing the latter from the well, means carried on the outer wall of said assembly for sealing the same against the inner wall of the tubing, whereby flow of fluid from the well will pass through said assembly, a choke member freely mounted in said assembly for relative movement with respect thereto under relatively high well pressure to position for restricting the area of flow of fluid through said assembly from the well, and relatively movable with respect to said assembly at relatively low well pressure to position for increased area of flow of fluid through said assembly from the well, and means for latching said assembly in flow controlling position in said tubing.

5. In a well, a tubing providing for flow of fluid from the well, a hollow choke assembly adapted to be lowered into said tubing to control flow of fluid therethrough from the well, and to be removed from said tubing without removing the latter from the well, means carried on the outer wall of said assembly for sealing the same against the inner wall of the tubing, whereby flow of fluid from the well will pass through said assembly, a choke member mounted in said assembly for relative movement with respect thereto under relatively high well pressure to position for restricting the area of flow of fluid through said assembly from the well, and relatively movable with respect to said assembly by gravity at relatively low well pressure to position for increased area of flow of fluid through said assembly from the well, and means for latching said assembly in flow controlling position in said tubing.

6. In a well, a tubing providing for flow of fluid from the well, a hollow choke assembly adapted to be lowered into said tubing to control flow of fluid therethrough from the well, and to be removed from said tubing without removing the latter from the well, means carried on the outer wall of said assembly for sealing the same against the inner wall of the tubing, whereby flow of fluid from the well will pass through said assembly, a choke member mounted in said assembly for relative movement with respect thereto under relatively high well pressure to position for restricting the area of flow of fluid through said assembly from the well, and relatively movable with respect to said assembly by gravity at relatively low well pressure to position for increased area of flow of fluid through said assembly from the well, and means for latching said assembly in flow controlling position in said tubing, and means for

releasing said latching means and removing said assembly from said tubing.

7. In a well, a tubing providing for flow of fluid from the well, a hollow choke assembly adapted to be lowered into said tubing to control flow of fluid therethrough from the well, and to be removed from said tubing without removing the latter from the well, means carried on the outer wall of said assembly for sealing the same against the inner wall of the tubing, whereby flow of fluid from the well will pass through said assembly, a choke member freely mounted in said assembly for relative movement with respect thereto under relatively high well pressure to position for restricting the area of flow of fluid through said assembly from the well, and relatively movable with respect to said assembly at relatively low well pressure to position for increased area of flow of fluid through said assembly from the well, and means for latching said assembly in flow controlling position in said tubing including springs which are depressed by said assembly moving into flow controlling position.

8. In a well, a tubing providing for flow of fluid from the well, a choke assembly seat in said tubing, a hollow choke assembly adapted to be lowered into said tubing in engagement with said seat to control flow of fluid through the tubing from the well, and to be removed from said tubing without removing the latter from the well, means carried on the outer wall of said assembly for sealing the same against the inner wall of the tubing, whereby flow of fluid from the well will pass through said assembly, a choke member freely mounted in said assembly for relative movement with respect thereto under relatively high well pressure to position for restricting the area of flow of fluid through said assembly from the well, and relatively movable with respect to said assembly at relatively low well pressure to position for increased area of flow of fluid through said assembly from the well, and means for latching said assembly in flow controlling position in said tubing.

9. In a well, a tubing providing for flow of fluid from the well, a hollow choke assembly adapted to be dropped into said tubing to control flow of fluid therethrough from the well, and to be removed from said tubing without removing the latter from the well, a restricted area in said tubing to receive said assembly at flow controlling position, means carried on the outer wall of said assembly for sealing the same against the inner wall of the restricted area of said tubing, whereby flow of fluid from the well will pass through said assembly, a choke member freely mounted in said assembly for relative movement with respect thereto under relatively high pressure to position for restricting the area of flow of fluid through said assembly from the well and relatively movable with respect to said assembly at relatively low well pressure to position for increased area of flow of fluid through said assembly from the well, and automatically operable means for latching said assembly in flow controlling position in said tubing when said assembly is dropped therein.

10. In a well, a tubing providing for flow of fluid from the well, a hollow choke assembly adapted to be dropped into said tubing to control flow of fluid therethrough from the well, and to be removed from said tubing without removing the latter from the well, a restricted area in said tubing to receive said assembly at flow controlling

position, means carried on the outer wall of said assembly for sealing the same against the inner wall of the restricted area of said tubing, whereby flow of fluid from the well will pass through said assembly, a choke member freely mounted in said assembly for relative movement with respect thereto under relatively high pressure to position for restricting the area of flow of fluid through said assembly from the well and relatively movable with respect to said assembly at relatively low well pressure to position for increased area of flow of fluid through said assembly from the well, automatically operable means for latching said assembly in flow controlling position in said tubing when said assembly is dropped therein, and means for releasing said latching means and removing said assembly from said tubing.

11. In combination with a well tubing, a well choke assembly for controlling flow of fluid therethrough from the well, said assembly being adapted to be lowered into and removed from the tubing, latching means for automatically latching said choke assembly in flow controlling position in said tubing, said assembly comprising a housing formed with a restricted lower end and a second restriction spaced upwardly from its lower end, and a choke member formed with an upwardly tapering passage mounted within said housing for sliding movement between the restricted lower end thereof and said second restriction. 5 10 15
